UNITED STATES PATENT OFFICE.

EUGÈNE LIGONNET, OF PARIS, FRANCE.

REINFORCEMENT.

Application filed December 5, 1924, Serial No. 754,174, and in France December 12, 1923.

This invention relates to helically-wound wire reinforcements, applicable more particularly to drain-pipes and other cylindrical or cylindro-conical articles made of reinforced cement, baked earthenware, rubber or other materials and produced by centrifugation or casting with the aid of compressed air or by other means; the invention presenting improvements upon reinforcements of this type wherein the adjacent convolutions of the main or circumferential helically-wound element of the reinforcement are secured at the required distance apart by their engagement between the adjacent convolutions of a plurality of spacing-members in the form of continuous wire helices of relatively small diameter each of which is held in position by means of a rod extending through it longitudinally.

In a wire reinforcement in the form of a grid for use in the construction of concrete roads, floors, walls and such like structures, and comprising layers of rods crossing one another at relatively wide intervals it has been proposed, for the purpose of attaching the several rods of one layer to a rod of the other layer, to provide a spacing-member constituted by a wire extending alongside of said rod of the second layer and presenting, at intervals corresponding with the spacing of the rods of the first layer, as many isolated sets of spiral bends; each rod of said first layer being received and gripped between adjacent convolutions of the corresponding set of spiral bends of the spacing-member, whilst what may be termed a locking-wire is passed through all the sets of spiral bends on the spacing-member so as to retain within them the rods of the first layer; there being as many of such spacing-members as there are rods of the second layer, so that the rods of the respective layers are held together at each crossing-point.

According to the present invention, which is applicable only to helically-wound reinforcements having continuously-wound spacing-members, two longitudinal rods are employed in combination with each spacing-member, the one rod extending inside and the other outside the main or circumferential helically-wound element, hereinafter referred to as the directrix; said longitudinal rods being placed opposite to one another upon that diameter of the continuous helix, constituting the spacing-member, which is

substantially coincident with that radius of the main or circumferential element which intersects the axis of said helix; and the joint thickness of the wires constituting the main or circumferential element and the inner and outer longitudinal rods being substantially equal to the internal diameter of the helical spacing-member so as, by fitting therein, to lock the spacing-member securely in position.

The spacing-members are temporarily received in recesses on the periphery of the mandrel. Each inner longitudinal rod, which may have its outer surface substantially flush with the outer surface of the mandrel, is hereinafter for convenience referred to as a generatrix; whereas each outer longitudinal rod is referred to as a locking-pin.

In addition to the various elements mentioned above, there may be employed one or more wires which are wound, as helices of steep pitch, externally of the directrix and in a direction contrary thereto, so as to prevent any tendency to distortion of the structure as a whole when freed from the support of the mandrel.

In the accompanying drawings which illustrate a typical embodiment of the invention, Figure 1 is a side elevation of the improved reinforcement, and Figure 2 is a cross section thereof, shown as mounted on a mandrel for purposes of assembling.

Into each helix *a* constituting a spacing-member is inserted a straight rod *b*, of steel or other metal, which constitutes a generatrix and is of the same length as the helix. As many generatrices *b* (provided with spacing-members *a*) as may be desired are arranged around a mandrel *c* of any collapsible type. At the points corresponding to the positions of the generatrices *b*, the mandrel is provided with recesses *d*, of the same shape as the helices *a* and of a depth which is determined by the gauge of the wire of the helix *a* and of the generatrix *b*. The generatrices *b* and helices *a* may be temporarily held in position in the recesses *d* of the mandrel by any convenient fastening means.

The directrix *e* is wound on the mandrel and over the generatrices *b* in the opposite direction to the winding of the helices *a*, and in such a way that its convolutions will come exactly into position between the con-

volutions of said helices, so that the latter act as spacing-members for the convolutions of the directrix, the elasticity of the two windings operating in opposite directions. When the desired length of directrix *e* has been wound, each of its ends is secured by tying or soldering, and the generatrices *b* are turned back over the last turns of the directrix *e*, so as to grip them in the manner shown on the left of Figure 1.

If at this moment the reenforcement were detached from the mandrel, it would suffer dislocation owing to the absence of ties. Consequently, before withdrawing the mandrel, a locking-pin *f*, consisting of a straight metal wire, is inserted through the outer part of each helix *a*. This locking-pin, which may be in several lengths, is bent back over the end convolutions, as indicated on the left in Figure 1. Each helix *a* thus holds the convolutions of the directrix *e* between the generatrix *b* and the locking-pin *f* (see Figure 2).

In addition, it is advisable to wind upon the exterior of the reenforcement a wire *g*, in the form of a helix of steep pitch, in a direction opposite to that of the winding of the directrix *e*. This wire *g* is also hooked at the ends. Its object is to prevent distortion of the reenforcement as a whole, or torsional movements of the directrix after separation from the mandrel.

Each helix *a* may be of cylindrical, oval, square or other shape in end view, its sectional dimensions being determined by those of the bar *b*, directrix *e* and locking-pin *f*, whilst the pitch of each helix *a* is determined by the sectional dimensions of the

directrix *e* and by the number of convolutions of the latter per unit of length.

The improved reenforcement is applicable not only to pipes, but also to posts or similar articles, and it permits of any commercial kinds of steel being used, whatever their strength.

The directrix may be wound by hand, or preferably on a machine by the aid of a leading-screw which gives a suitable pitch.

What I claim is:—

1. A wire reenforcement for cement pipes comprising in combination a helically-wound main element, a plurality of helically-wound spacing members, the convolutions of said spacing members being spaced apart a distance equal to the distance between the convolutions of the main element, and two longitudinal rods within each of said spacing members, one of said rods being on the inside and the other on the outside of said main element.

2. A wire reenforcement for cement pipes comprising in combination a helically-wound main element, a plurality of helically-wound spacing members, the convolutions of said spacing members being spaced apart a distance equal to the distance between the convolutions of the main element, two longitudinal rods within each of said spacing members, one of said rods being on the inside and the other on the outside of said main element, and a plurality of helical members of steep pitch wound upon said main element.

In testimony whereof I hereunto affix my signature.

EUGÈNE LIGONNET.
